BASE OR PEDESTAL FOR CHAIRS

Filed Jan. 16, 1947

INVENTOR.

BY *John A. Earl*
Attorney

UNITED STATES PATENT OFFICE

2,587,886

BASE OR PEDESTAL FOR CHAIRS

Henry A. Penchoen, Sturgis, Mich., assignor to
Harter Corporation, Sturgis, Mich., a corporation of Michigan

Application January 16, 1947, Serial No. 722,435

6 Claims. (Cl. 248—194)

1

This invention relates to improvements in bases or pedestals for chairs.

The main objects of this invention are:

First, to provide a chair pedestal or base which may be formed mainly as an integral stamping and which is strong and rigid and is attractive in appearance.

Second, to provide a chair pedestal or base which may be economically produced and is very strong and rigid even when formed of light gauge stock.

Objects relating to details and economies of the invention will appear from the description to follow. The invention is defined in the claims.

A structure which embodies the features of the invention is illustrated in the accompanying drawings, in which:

Fig. 1 is an elevational view of a structure embodying the invention sectioned on line 1—1 of Fig. 2, the seat post or spindle being partially broken away.

Fig. 2 is an inverted view of the pedestal with the castors omitted, part of the bottom plate being broken away to show structural details.

Fig. 3 is an enlarged fragmentary view in vertical section on line 3—3 of Fig. 2.

Fig. 4 is an enlarged fragmentary view in vertical section on a line corresponding to line 4—4 of Fig. 2.

Fig. 5 is a transverse section on line 5—5 of Fig. 4.

Fig. 6 is a fragmentary section similar to that of Fig. 3 showing the relation of the seat post supporting and adjusting nut relative to the spindle socket.

The embodiment of the invention is of a revolving office type of chair. The chair seat post or spindle 1 is provided with a threaded portion at its lower end to coact with the adjusting and supporting nut 101.

The base or pedestal of my invention consists of a body member comprising a central hub portion 2 and radial arms 3 formed integrally therewith preferably as a hollow sheet metal stamping. It might, however, be formed as a casting as the parts are shaped so as to permit the use of very thin stock, at the same time provide strength and rigidity. The hub portion is chambered and the arms are of channel section. The side walls 4 of the arms merge into the side walls 5 of the hub portion.

The top walls 6 of the arms merge into the top 7 of the hub portion which in the embodiment illustrated has a cruciform boss 8 struck therefrom, the arms of the boss being aligned with the

2

arms of the base. This boss adds materially to the rigidity of the top wall of the structure and also reinforces the structure as the top wall merges into the arms.

5 The top and side walls of the arms merge into rounded ends 9. These rounded ends have lugs 10 struck inwardly therefrom. The side walls of the arms have inturned flanges 11 which terminate in spaced relation to the ends of the arms, the side and end walls at the ends of the arms extending downwardly at 13 substantially below the flanges, the side portions of the walls being upturned at 14 to provide a rounded surface and a reinforcement.

10 15 Castor socket plates 15 provided with castor sockets 16 are disposed within the walls of the arms at the ends thereof with their outer ends in positioning engagement with the lugs 10 and their inner ends with the flanges 11 which they 20 preferably overlap as shown in Fig. 4. These castor socket plates are welded as indicated at 12 to the inner sides of the walls as best shown in Fig. 5.

25 Cap or bumper nose pieces 17 are provided, 25 these serving as bumper or wear plates and also reinforcing the end of the arms. These cap members have inturned flanges 18 engaging the end walls of the arms, the caps being conformed to fit the walls and being further secured by the bolts 19. The castor socket plates also serve to reinforce the walls at the ends of the arms.

The bottom plate 20 is of general cruciform shape and fits within the side walls of the hub portion and is welded thereto as indicated at 21.

30 35 This bottom plate serves to reinforce the walls of the base at the central or hub portion thereof and it also serves as a support member for the spindle socket 22. This spindle socket is formed as a tube desirably of sheet metal and is arranged through the hole 23 in the bottom plate, an aligned hole 24 in the top of the hub portion, and the hole 25 of the spindle socket supporting plate 26.

35 40 The spindle socket is welded at 27 to the under side of the plate 26 and the plate 26 is welded as indicated at 28 to the top of the hub portion. The spindle socket plate has a central upset portion to accommodate the weld 27 and it also serves as a finish member.

45 50 The wall of the spindle socket is upset axially to provide an annular bead 30 which rests on the socket plate. The spindle socket is provided with a flange 31 serving as a bearing for the adjusting nut 101. This provides a very strong and rigid structure and at the same time one which 55 is highly attractive in appearance.

I have illustrated and described my invention in a very practical commercial embodiment thereof. I have not attempted to illustrate or describe certain modifications and adaptations, as it is believed that this disclosure will enable those skilled in the art to embody or adapt the invention as may be desired.

Having thus described my invention, what I claim as new and desire to secure by Letters Patent, is:

1. The combination in a chair pedestal or base, of a body member comprising a central chambered hub portion and radial arms formed integrally therewith as a hollow stamping, the arms being of downwardly facing channel section, the sides and top thereof merging with the sides and top of the hub portion, the sides of the arms merging into rounded closed ends, the sides of the arms having inturned bottom flanges terminating in spaced relation to the ends of the arms, the sides beyond such flanges extending below the flanges with the bottom edges thereof turned inwardly and upwardly against the sides, castor socket plates disposed within the ends of the arms and welded to the walls thereof, a cruciform bottom plate fitting within the side walls of the hub portion and welded thereto, the top wall of the hub portion having a cruciform boss struck up therefrom with the arms thereof aligned with the arms of the body member, a spindle socket plate disposed on and welded to said boss and having a central upset portion, said socket supporting plate, the top of said hub portion and said bottom plate having aligned openings therein, and a tubular spindle socket disposed through said openings and welded to said socket supporting plate and bottom plate.

2. The combination in a chair pedestal or base, of a body member comprising a central chambered hub portion and radial arms formed integrally therewith, the arms being of downwardly facing channel section, the sides and top thereof merging with the sides and top of the hub portion, the sides of the arms merging into closed ends, the ends of the arms having inturned lugs spaced from the bottom edges thereof, the sides of the arms having inturned bottom flanges terminating in spaced relation to the ends of the arms, the sides beyond such flanges extending below the flanges with the bottom edges thereof turned inwardly and upwardly against the sides, castor socket plates disposed within the ends of the arms with their outer ends positioned against the under sides of said inturned lugs and their inner ends overlapping said side wall flanges, said plates being welded to the side walls and to said flanges, and arm caps embracing the ends of the arms, the front edges of said caps being turned inwardly and upwardly to engage the edges of the ends of the arms, the inner ends of the caps being secured to the tops of the arms.

3. The combination in a chair pedestal or base, of a body member comprising a central chambered hub portion and radial arms formed integrally therewith, the arms being of downwardly facing channel section, the sides and top thereof merging with the sides and top of the hub portion, the sides of the arms merging into closed ends, castor socket plates disposed within the ends of the arms and welded to the walls thereof, and arm caps embracing the ends of the arms, said ends of the arms providing flanges integral therewith and projecting below said castor socket plates, the front edges of said caps being turned inwardly and upwardly to engage around the

lower edges of said flanges at the ends of the arms, the inner ends of the caps being secured to the tops of the arms.

4. The combination in a chair pedestal or base, of a stamped body member comprising a central chambered hub portion and radial arms formed integrally therewith, the arms being of downwardly facing channel section, the sides and top thereof merging with the sides and top of the hub portion, the sides of the arms merging into closed ends, the ends of the arms having inturned lugs spaced from the bottom edges thereof, the sides of the arms having inturned bottom flanges terminating in spaced relation to the ends of the arms, the sides beyond such flanges extending below the flanges with the bottom edges thereof turned inwardly and upwardly against the sides, and castor socket plates disposed within the ends of the arms with their outer ends positioned against the under sides of said inturned lugs and their inner ends overlapping said side wall flanges, said lugs above the castor plates constituting means to transmit the weight of the pedestal to said castor plates, said plates being welded to the side walls and to said flanges.

5. The combination in a chair pedestal or base, of a body member comprising a central chambered hub portion and radial arms formed integrally therewith as a hollow stamping, the arms being of downwardly facing channel section, the sides and top thereof merging with the sides and top of the hub portion, the sides of the arms merging into rounded closed ends, a cruciform bottom plate fitting within the side walls of the hub portion and welded thereto, the top wall of the hub portion having a boss struck up therefrom with the arms thereof aligned with the arms of the body member, a spindle socket plate disposed on and welded to said boss and having a central upset portion, said socket supporting plate, the top of said hub portion and said bottom plate having aligned openings therein, and a tubular spindle socket disposed through said openings and welded to said socket supporting plate and bottom plate.

6. The combination in a chair pedestal or base, of a body member comprising a central chambered hub portion and radial arms of downwardly facing channel section formed integrally therewith, the sides and tops of the arms merging with the sides and top of the hub portion, the sides of the arms merging into end walls having inturned lugs struck therefrom, the sides of the arms having inturned bottom flanges, and castor socket plates disposed in supporting engagement with said lugs, the side walls of the arms extending substantially below said castor socket plates and being folded inwardly.

HENRY A. PENCHOEN.
